UNITED STATES PATENT OFFICE.

EMANUEL BLAUHORN AND OTTO HAJEK, OF VIENNA, AUSTRIA.

VARIABLE-STROKE FLUID PUMP.

Application filed October 20, 1920. Serial No. 418,291.

(GRANTED UNDER THE PROVISIONS OF THE ACT OF MARCH 3, 1921, 41 STAT. L., 1313.)

To all whom it may concern:

Be it known that we, EMANUEL BLAUHORN and OTTO HAJEK, citizens of the Republic of Austria, residing at Vienna, in the Republic of Austria, have invented certain new and useful Improvements in Variable-Stroke Fluid Pumps, of which the following is a specification.

This invention relates to a valveless pump 10 for liquids, by means of which two places may be served under either the same or different pressures by a single pump piston.

The pump comprises a piston which is moved by means of a cam-shaped disc 15 through the intermediary of an oscillating lever having a variable stroke, in such a manner that the piston performs two strokes at each revolution of a driving shaft, while the distributing piston performs only one 20 stroke at each revolution of the shaft with which it is connected by means of an eccentric.

According to this invention the piston performs a complete reciprocation at each 25 half revolution of the driving shaft and this by a positive driving mechanism acting in both directions. This mechanism consists of a double cam, cooperating with an actuating lever having two fingers or lugs, one of 30 which preferably is provided with an antifriction roller. The other finger or lug of said lever carries an internally threaded sleeve through which extends a screw spindle. The antifriction roller carried by one 35 finger or lug of said lever and the end of said screw spindle carried by the other finger or lug bear alternately upon said cam. The shape of the cam and the position of the finger or lug which carries the free end of 40 the screw spindle and that which carries the antifriction roller are so chosen, that the cam impinges only upon the end of the spindle or the roller at one time; but when the cam ceases to contact with the free end of 45 the spindle or with the roller, it comes immediately into contact with the other and begins to move it, whereby the lever controlling the piston movement is continually positively moved to and fro by the double 50 cam. The two faces of the double cam now cause a movement in both directions during one half revolution of the cam.

This arrangement makes it possible to use the same shaft for controlling both pistons, 55 one of them being moved by the said double

cam with a double speed, so that it performs a complete reciprocation while the other is moved by an ordinary cam embraced by a fork or double lever contacting with two opposite faces of the same once in one direction at each half revolution of the shaft.

In the accompanying drawing:—

Fig. 1 shows an elevation of the pump partly in section, the distributing and pump pistons being in different vertical planes.

Fig. 2 shows a top view of the driving shaft with the cams and actuating levers.

1 is the pump piston, working in the cylinder 1' and 2 is the distributing piston. According to the position of the distributing 70 piston 2, the liquid is forced either through channel 3 or through channel 4. 5 is the intake of the oil. If, for example, the steam inlet to a cylinder were closed, lubricating oil might be supplied through the channel 75 3 to the cylinder at low pressure and at another time through the channel 4 to the steam chest at the pressure of the boiler, according to the positions of the pump piston 1 and the distributing piston 2.

The pistons are reciprocated by the following driving mechanisms.

On the driving shaft 6 a double cam 7 which is provided with two eccentric faces is fixedly mounted. A rocking lever 8 is 85 connected with the pump piston 1 by means of a finger which extends into a slot of the said piston or is otherwise connected therewith in such a manner, that relative movement of the connected parts is possible.

The said rocking lever 8 is provided with a pair of additional fingers or lugs 12 and 13 which project into proximity to the periphery of the cam 7, both of said fingers or lugs 12 and 13 being bifurcated. An antifriction roller 14 is rotatably mounted in the bifurcation of the finger or lug 12, and an internally screw-threaded sleeve 15 is mounted to rock on pivots in the bifurcation of the finger or lug 13. The spindle 9 is screw-threaded adjacent its lower end to engage the internal screw-threads of the sleeve 15 and has its lower end projecting below the lower end of said sleeve into the path of the cam 7. The faces of the double cam 7 are so shaped that only the end of the spindle carried by one finger or lug or the roller carried by the other finger or lug will contact with the periphery of the cam at one time. When the cam, while rotating with the shaft and press-

ing upon the end of the spindle 9 carried by one finger or lug, moves out of contact with the end of said spindle, it immediately engages the roller carried by the other finger or lug and begins to press upon the same whereby the lever is rocked in opposite direction. As the cam is provided with two faces and the lugs or fingers are arranged approximately at a right angle to one another, each 10 half rotation of the shaft will cause a complete reciprocation of the pump piston 1, since once during each half revolution of the shaft one of the two faces of the cam impinges first upon the free end of the spindle 15 9 and then upon the roller carried by the respective lugs or fingers thus moving the rocking lever 8 in both directions. During the other half revolution of the shaft the second face of the double cam imparts the 20 same movement to the lever and the piston 1.

It will be seen from the above that the whole movement of the piston is positively controlled by the double cam cooperating with the end of the spindle 9 and the anti-friction roller carried by the respective fingers or lugs.

The distributing piston 2 is driven by an eccentric 10 mounted on the driving shaft 6 at an angle of 90° to the cam 7, the drive 20 being through a rocking lever 11 provided with a fork at one end, which encloses the eccentric in the well known manner, while the other end is provided with a finger extending into a slot of the distributing piston 25 2 or being otherwise connected with said piston in such manner that relative movement of the parts is permitted.

Thus it will be seen that the piston 1 performs two strokes for every stroke of the piston 2, the latter having an advance of one half stroke owing to the fact that both eccentrics are keyed on the shaft at an angle of 90°. Both pistons are positively driven during their whole stroke and the above arrangement makes it possible, notwithstanding such positive driving, to have both driving eccentrics mounted on the same driving shaft.

What we claim is:

50 1. In a valveless fluid pump having a pump piston and a distributing piston, means to reciprocate both pistons positively comprising a driving shaft, a cam on said driving shaft, a rocking lever in operative connection with the distributing piston, a fork on said lever enclosing the cam to effect

positive control of the movement of said lever, a second cam on said driving shaft provided with a pair of faces, a rocking lever adjacent to said second cam in operative connection with the pump piston, and two lugs on said lever adapted to come alternately in operative contact with each of the faces of said pair to effect positive driving of the piston in both directions at a speed 65 double to that of the distributing piston.

2. In a valveless fluid pump having a pump piston and a distributing piston, means to reciprocate both pistons by positive drive, comprising a single driving shaft, 70 two cams fixed on said shaft, a rocking lever in operative connection with one of said cams and the distributing piston, a second rocking lever in operative connection with the pump piston, the latter lever being provided with two lugs extending in proximity to the periphery of the second cam, a pair of faces on said second cam extending in different directions and impinging upon said lugs, the lugs of the second-named lever 75 being arranged in such a manner that they are alternately contacting with each of the faces of said second-named cam and are moved thereby in different directions at the passage of each of the faces as to effect positive movement of the piston by means of the rocking lever in both directions at a speed double to that of the piston moved by the other cam.

3. In a valveless fluid pump having a pump piston and a distributing piston, means to reciprocate both pistons by positive drive, consisting of a driving shaft, a cam keyed on said shaft, a rocking lever in operative connection with the cam and the pump piston, 90 a second cam provided with two faces keyed on the shaft at an angle of 90° to the first cam, a rocking lever provided with two lugs arranged at approximately a right angle to one another and adapted to come alternately 95 in contact with each of said faces, each of the faces effecting a positive to and fro movement of the rocking lever and of the piston connected therewith, the pump piston being reciprocated twice by means of the two faces 100 during one reciprocation of the distributing piston.

In testimony whereof we have hereunto set our hands.

EMANUEL BLAUHORN.
OTTO HAJEK.
